UNITED STATES PATENT OFFICE.

LOUIS SCHUTTE, OF PHILADELPHIA, AND AXEL S. VOGT, OF ALTOONA, PENNSYLVANIA.

OIL-TORCH.

SPECIFICATION forming part of Letters Patent No. 566,024, dated August 18, 1896.

Application filed October 23, 1894. Serial No. 526,899. (No model.)

To all whom it may concern:

Be it known that we, LOUIS SCHUTTE, a citizen of the United States, residing in Philadelphia, in the county of Philadelphia, and 5 AXEL S. VOGT, a subject of the King of Sweden and Norway, residing in Altoona, county of Blair, State of Pennsylvania, have invented a new and Improved Oil-Torch, of which the following is a specification, reference being 10 had to the accompanying drawings, which form a part thereof.

Our invention relates to oil-torches, and has for its object to provide a portable torch which can be advantageously employed to 15 start a fire in the furnaces of locomotive and other boilers.

Our invention consists mainly in providing a portable receptacle with a nozzle connected with the space near the bottom, through which 20 nozzle the oil can be forced in a jet or spray, and with an inlet or inlets through which air under pressure or such air and the oil charge can be introduced into the receptacles. Preferably we provide independent inlets for the 25 introduction of oil and air, and we provide, of course, a valve or valves for governing the inlet and outlet passages.

Our invention further consists in details of construction which will be fully described in 30 connection with the accompanying drawings, in which—

Figure 1 shows the preferred form of our torch in position in front of a locomotive-furnace. Fig. 2 is an enlarged detail view of 35 the inlet-openings and the oil-nozzle in our preferred form of torch, the section being taken at right angles to that shown in Fig. 3. Fig. 3 is a vertical section of the torch, taken at right angles to the section of Fig. 2. Fig. 40 4 is a view on the line 4-4 of Fig. 2, the nozzle and air-pipe being removed; and Fig. 5 is a view similar to that shown in Fig. 4, the valve being shown in a different position.

A indicates a receptacle for oil and compressed air, which, while it may be constructed of sheet metal, is preferably made of cast metal, as indicated in the drawings, so as to have as few seams and joints as possible. The 45 substantially oval shape shown is a very convenient one, though the receptacle may be made in any desired shape.

B is a head or cover, in which we preferably form the inlet opening or openings for the oil and air and an outlet-opening for the oil.

The outlet-opening is connected with the 55 bottom of the receptacle, so as to take its charge therefrom. As shown, the outlet-opening b⁵ is connected by means of a passage b⁵ and a pipe D to the space near the bottom of the receptacle A.

The inlet-opening b for oil is preferably connected to the same passage b⁵ as is also the air-inlet opening b², the single valve C controlling all three openings. It will of course be obvious that the oil and air can be 65 introduced into the receptacle through the same opening, and also that two or more valves can be employed to control the inflow of oil and compressed air and the outflow of the oil, but we much prefer the arrangement 70 shown, where one valve controls all the openings. This valve C is shown as a plug-valve operated by a handle c', and is provided with a port c', which is adapted, when the valve is properly turned, to register with one of the 75 openings b, b¹, or b² and connect it through the chamber c² and port c' with the passage b⁵. A passage c³ in the valve also controls the vent-port b³. This passage is so arranged that it will open the vent-port when the port 80 c registers with the oil-inlet opening b, as shown in Fig. 3.

Around the oil-inlet b is conveniently formed a funnel B⁵, formed integral with the head B, through which funnel the oil may be 85 poured.

The pipe D extends, as has been said, down near the bottom of the receptacle. A second pipe D' extends into the receptacle or tank A and connects at its upper end with the vent-port b³.

It will be noticed that when the valve C is in the position shown in Fig. 1 the air in the upper part of the tank can escape freely through the pipe D' and the port b³ till the 95 oil closes the bottom of the pipe D'. If any more oil is poured into the pipe D, the air in the upper part of the receptacle will be somewhat compressed and will force the oil up the pipes D and D', and when oil appears at the 100 vent-port b³ this will indicate to the operator that the tank is sufficiently filled. By using

a shorter or longer pipe D' a greater or less charge of oil can be given the torch, and we prefer to so proportion the parts that one charge of oil given the torch will be sufficient 5 to kindle one fire.

The nozzle F, through which oil is forced from the receptacle, can of course be of any suitable form; but we prefer to employ a nozzle which gives a whirl to the oil escaping 10 from it.

The nozzle F is shown connected to a short pipe F', secured on the head B and opening from the passage b', a strainer f being conveniently inserted in the pipe F', as shown.

15 It is also preferable, especially when the torch is employed in connection with locomotive-furnaces, to provide the air-inlet opening with a hose, as E, which is furnished with a coupler E', such as are employed to connect 20 the various lengths of hose in an air-brake system, so that the air-inlet may be connected to the compressed-air reservoir of such a system, as indicated in dotted lines of Fig. 1, and the reservoir given a charge of compressed 25 air from this reservoir. It is, however, to be understood that the compressed air can be introduced into the torch in any way. For instance, a hand air-pump may be employed either to give the receptacle a charge of compressed 30 air before the torch is used to start a fire or to force out oil during its use. Also, while we prefer for the sake of convenience to arrange the parts as shown in Figs. 2 and 3 and to connect the nozzle to the space near 35 the bottom of the receptacle by the pipe D, it will be evident that the nozzle may itself be situated near the bottom of the tank, or that after being charged the tank can be turned upside down and the pipe D dispensed 40 with.

The torch is portable, and we provide it with handles A', as best shown in Fig. 1, to aid in transporting it, and also when it is of the oval shape shown it is provided with feet 45 a a, cast with the tank A. By securing the pipes D D' to the cover B, as shown, they are conveniently removable with it. After the tank has been given its charge of oil and air, as described, the torch is placed in position 50 in front of a furnace, as indicated at L', Fig. 1, and the oil-outlet opened. The oil will be forced out in a spray or jet by the pressure

of the air, and when ignited will quickly start the fire. If a proper charge of oil has been given the torch, it may be left alone after it 55 is in position and started, as it will continue operating till it has blown itself out.

Having now described our invention, what we claim as new, and desire to secure by Letters Patent, is—

1. A portable oil-torch consisting of a suitable receptacle for oil and compressed air and having an outlet-nozzle for oil arranged so as to draw its supply from the bottom of the receptacle, independent inlets for oil and compressed air, and a single valve adapted to govern both inlet-openings and the passage 65 leading to the outlet-nozzle.

2. A portable oil-torch consisting of a receptacle for oil and compressed air having an 70 inlet-opening for oil and an outlet-nozzle, a valve for controlling these openings, a pipe D, extending to near the bottom of the receptacle and connecting to the oil inlet and outlet openings, a second pipe D', connected to a vent-opening also controlled by the valve and projecting into the receptacle a less distance than the pipe D as described, whereby 75 a definite charge of oil can be given the receptacle.

3. A portable torch consisting of a receptacle A for oil and compressed air, a cover B therefor having inlet-openings for oil and air and an oil-outlet opening therein and a valve 85 for controlling these openings, and pipes D and D' secured to the cover B so as to be removable therewith.

4. A portable oil-torch consisting of a receptacle A for oil and compressed air, a cover or head B therefor having an oil-inlet opening provided with a funnel B² an inlet for air and an oil-outlet and pipes D and D' secured to the head B and extending down into the receptacles for different distances as described.
